UNITED STATES PATENT OFFICE.

CHARLES H. SIMMONS, OF NEW YORK, N. Y.

DESIGN FOR A STAND-PIPE Y CONNECTION.

SPECIFICATION forming part of Design No. 35,157; dated October 1, 1901.

Application filed April 15, 1901. Serial No. 56,017. Term of patent 14 years.

To all whom it may concern:

Be it known that I, CHARLES H. SIMMONS, a citizen of the United States; and a resident of New York, in the county and State of New York, have invented and produced a new and original Design for a Stand-Pipe Y Connection, of which the following is a specification.

Figure 1 is a front elevation of the whole device. Fig. 2 is a view of the right-hand downwardly-drooping branch of the Y connection in perspective, so as to show that portion of the design which is invisible in Fig. 1. It shows especially the cylindrical rim L around the hole F at the back of the device and also the contour of the lugs I and I', not clearly determined by Fig. 1.

As shown in the drawings, my design consists of the flattened partially-circular portions or faces A on the upper outside of the connection. The further exterior configurations of the design are as follows.

The device as a whole is a drooping or inclined Y connection, with the common entrance-opening F on the back for joining to a water stand-pipe—for example, in a tall building. Two branch pipes of cylindrical exterior extend outward and downward and are terminated by cylindrical caps E, locked to the device by chains G, which hang downward in a graceful sinusoid from the ends of the caps to the ring K in the lug I', which is at the lower part of the juncture of the two branches. Another lug I is at the upper

part of the same juncture. The lugs I and I' are curved projections formed upon the lower and upper parts of the Y connection. The lower one points down and the other up. H represents two other lugs, of semicylindrical shape, on the tops of the branches and at the lower edges of the flattened portions A. They are pierced to form holes at the central parts.

The material or leading features of the design are the flattened partially-circular portions or faces A on the upper portion of each of the two branch pipes, the lugs I', the caps E, locked to the device by chains G, which hang downward in a sinusoidal curve from the ends of the caps to the lug I', the corresponding lug I, symmetrically arranged, being on the top, while the lug I' is on the lower part of the device at the juncture of the two branches, and the lugs H, terminating the flattened portions A.

Having described my invention, what I claim as new, and desire to secure by Letters Patent, is—

The design for a stand-pipe Y connection, as herein shown and described.

In testimony whereof I have hereunto subscribed my name this 22d day of March, 1901.

CHAS. H. SIMMONS. [L. S.]
